UNITED STATES PATENT OFFICE.

KENNETH J. UNWIN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR IN LOOM TRANSFERRERS.

Application filed November 10, 1927. Serial No. 232,425.

This invention relates to improvements in weft detectors for regularly moving transferrer arms and it is the principal object of the invention to provide a side slipping weft detector which shall be moved as a unit in a direction substantially parallel to the bobbin being detected and at the same time so controlled and actuated as to provide maximum clearance between the front wall of the shuttle and the detecting element as the lay moves rearwardly.

In co-pending application Ser. No. 232,432 filed by Cederlund there is set forth a transferrer arm on which is slidably mounted a detector carrier movable in the direction of the length of the bobbin being detected. The purpose of this construction is to prevent the angular motion of the detecting element with respect to the transferrer arm such as has heretofore been customary in side slipping weft detectors in transferrer arms. In that application the detector is held yieldingly in its lowest position so that as the transferrer arm rises the detecting element does not move upwardly immediately but remains in low position until some time after the transferrer arm starts its upward movement. The result of this is to lessen the clearance between the detecting element and the front wall of the shuttle and it is an important object of my present invention to provide a side slipping weft detector mounted on a sliding carrier which shall be normally in raised position and will be lowered into contact with the yarn being detected so that as the transferrer arm starts upwardly after reaching its lowest position the detector element will also immediately rise to provide increased clearance with the front wall of the shuttle.

It is a further object of the invention to provide means for moving the detecting element downwardly into engagement with the yarn before the transferrer arm arrives at the bottom of its stroke and also to employ a weighted element which tends to move the detector carrier and the detector in a direction parallel to the bobbin after the transferrer arm has reached the lower limit of its travel and after the detecting element is in contact with the yarn.

With these and other objects in view which will appear as the description proceeds, my invention resides in the combination and

arrangement of parts hereinafter described and set forth in the claims.

In the accompanying drawings wherein one form of my invention is shown,

Fig. 1 is a vertical section through that part of the transferrer arm which extends over the bobbin, the parts being in the position they assume when there is a sufficient supply of weft and the transferrer arm is in its lowest position,

Fig. 2 is a view similar to Fig. 1 but with the parts moved to the position they assume when indicating substantial exhaustion of weft,

Figs. 3 and 4 are vertical sections on line 3—3 and 4—4, respectively, of Fig. 1 looking in the direction of the arrows, and

Fig. 5 is a fragmentary top plan view taken in the direction of arrow 5, Fig. 2.

Referring to the drawings the transferrer arm 10 is provided with a horizontal extension 11 having spaced vertical walls 12 which define a vertical slot 13 in which are housed the detecting and indicating mechanisms. An indicating plunger 14 is slidable in bearings 15 and 16 carried by the transferrer arm, the bearing 16 being mounted in a web 17 which connects the walls 12. An indicating lever 18 is provided adjacent one end of the transferrer arm as shown in Figs. 1 and 2 and is the means by which the indication of weft exhaustion is communicated to the weft replenishing mechanism not shown but well known in the art.

A compression spring 19 surrounds a portion of the plunger 14 and lies between a pin 20 in said plunger and the forked arm 21 of an actuator 22 pivoted on a pin 23 secured in the walls 12. Said actuator is provided with a pair of spaced weighted arms 24 as shown in Figs. 1, 4 and 5 and which lie to one side of the pivot pin 23. This actuator is also provided with a stop portion 25 which connects the weighted arms 24 and serves when the actuator is in normal raised position to prevent movement of the plunger by means of mechanism to be described.

A detector carrier 26 is bolted to the left end of the plunger 14 and extends upwardly between and is slidable along spaced horizontally aligned lugs 27 formed on the walls 12. Said carrier has a stop finger 28 projecting to the right and so located as to be in horizontal alignment with the normal

raised position of the stop portion 25. This carrier also has a pair of spaced horizontal arms 29 in which is mounted for vertical yielding movement the detecting element 30 which as shown in Fig. 5 may be formed of sheet metal. The lower end of this detecting element extends horizontally as at 31 and is provided with teeth 32 which cooperate with the yarn to prevent movement of the carrier and detector element in a horizontal direction substantially parallel to the bobbin B when sufficient weft is present. The matter thus far described is shown in a co-pending application No. 232,422, filed by Wakefield 15 and forms no part of my present invention except that the weighted arms 24 are separated to define a space for an operating element to be described hereinafter whereas in the above Wakefield application a single 20 weight has been used.

In carrying my invention into effect I pivot a depressor lever 40 on a pin 41 extending between the walls 12 and project the same to the right having an offset lug 42 positioned for engagement with a yielding trip 43 of the type shown in patent to Ryon No. 1,551,219. Said depressor lever is extended between the weighted arms 24 as shown in Figs. 1, 4 and 5 and also extends 25 through a slot 44 formed in the carrier 26 by striking out the stop finger 28. The left end of said depressor lever is forked as at 45 to define a space through which the upper end of the detector element 30 extends. A 30 washer 46 is held against the bottom of the fork by means of a pin 47 and a compression spring 48 interposed between said pin and the lower horizontal arm 29 of the carrier 26. The dual effect of said spring 40 48 is to hold both the detector element 30 and the left end of the depressor lever 40 in yielding raised position.

In operation the transferrer arm when in raised position would start its downward movement with the weighted actuator 22 in its normal position indicated in dotted lines in Fig. 1 relatively to the transferrer arm and with the stop portion 25 in horizontal alignment with the stop finger 28 thereby holding the plunger 14 to the left as viewed in Fig. 1 in non-indicating position and with the compression spring 48 holding the detector and the left end of the depressor lever in raised position. As the transferrer arm descends the lug 42 will engage the yielding trip 43 to cause the left end of the depressor lever to move downwardly against the washer 46 and the pin 47 passing through the detector element 30. In this way the detector is moved from its normally raised position to its lower or detecting position at some time prior to the arrival of the transferrer arm at the bottom of its stroke and as the transferrer continues to move downwardly the teeth 32 will engage the bobbin 55 60 65

and if sufficient yarn is present will be embedded therein.

When the transferrer arm reaches the lower limit of its movement the weighted arms 24 being free to move about the pin 23 will continue to move downwardly because of their momentum and in doing so will move the forked arm 21 to the right as shown in Figs. 1 and 2 to further compress the spring 19 and also to cause the stop portion 25 to move below the stop finger 28. When sufficient yarn is present the detector will be prevented from moving to the right when said stop portion 25 frees the stop finger 28 and the spring 19 is placed under additional strain. As soon as the momentum of the weighted arms 24 is spent the spring 19 will extend to restore the actuator 22 to its normal position relatively to the transferrer arm causing the stop portion 25 to move in the path of the stop finger 28. This action takes place very shortly after the transferrer arm has arrived at the bottom of its stroke and before the transferrer arm has risen far enough to permit the teeth 32 to move away from the yarn on the bobbin.

When insufficient yarn for continued weaving is present, however, the detector teeth 32 will not be held by the surface being detected against horizontal movement and as the stop portion 25 moves away from the stop finger 28 and the spring 19 is placed under additional strain the detector and its carrier 26 together with the plunger 14 will be moved to the right or to the indicating position shown in Fig. 2, the stop finger 28 passing between the weighted arms 24 and the detector moving horizontally in the fork 45. When the transferrer arm is at the bottom of its stroke on an indicating beat of the loom therefore the plunger will be moved to the right to lie under the indicating lever 18 and as the transferrer arm moves upwardly said plunger will rock the indicating lever as described in the aforesaid patent to Ryon. Upon continued upward movement of the transferrer arm the plunger 14 will engage an inclined cam face 60 on the indicating lever which will cause said plunger to be moved to the left against the action of spring 19 to move the stop finger 28 out of vertical alignment with the stop portion 25. When this latter action takes place the spring 19 will move the actuator 22 in a clockwise direction around the pin 23 to restore the parts to normal position with the stop portion 25 positioned to limit movement of the finger 28 and therewith the plunger 14.

From the foregoing it will be seen that I have provided a weft detecting element mounted to slide relatively to the transferrer arm and so arranged as normally to be in raised position and it will also be seen that

the depressor lever acts to yieldingly move the indicating element downwardly into engagement with the yarn prior to the movement of the stop portion of the actuator 5 away from the stop finger of the carrier.

Having thus described my invention it will be seen that changes and modifications may be made therein by those skilled in the art without departing from the spirit and 10 scope of the invention and I do not wish to be limited to the details herein disclosed, but what I claim is:

1. In weft detecting mechanism for a loom having a regularly moving transerrer arm 15 provided with an indicating plunger normally in non-indicating position, a detector carrier slidably mounted relatively to the transerrer arm and operatively connected thereto said carrier being movable in a direction substantially parallel to the surface being detected, a detecting element movably mounted in the carrier and held yieldingly in raised position, a depressor element to lower the detecting element relatively to the carrier 20 during the downward movement of the transerrer arm, and means operative after the detector has engaged the surface to be detected tending to move said carrier in the direction of the length of the surface 25 being detected, and movement being prevented when the detector engages a sufficient supply of weft.

2. In weft detecting mechanism for a loom having a regularly moving transerrer arm 30 provided with an indicating plunger normally in non-indicating position, a detector carrier slidably mounted relatively to the transerrer arm and operatively connected thereto, said carrier being movable in a direction substantially parallel to the surface being detected, a vertically disposed detecting element supported by and movable relatively to the carrier, yielding means holding the detecting element normally in raised position 35 relatively to the carrier, depressing means operative during the downward movement of the transerrer arm to act against the yielding means and lower the detecting element relatively to the carrier, and means effective after the detector element has been moved to low position tending to move the detector along the surface being detected in a direction substantially parallel to the latter, and movement being prevented when 45 the detector engages a sufficient supply of weft.

3. In a weft detector for a loom having a regularly moving transerrer arm provided with an indicating plunger slidably mounted 50 on the transerrer arm and normally in non-indicating position, a detector carrier secured to and moving with the indicating plunger in a direction substantially parallel to the length of the surface being detected, 55 a vertically disposed weft detecting element

mounted in the carrier for relative movement with respect thereto, yielding means to hold the detector element normally in raised position relatively to the carrier, means to lower the detector element relatively to the carrier 70 during the downward movement of the transerrer arm, and means to thereafter tend to move the detector carrier and indicating plunger in a direction substantially parallel to the length of the surface being 75 detected, and movement being prevented when the detector engages a sufficient supply of weft.

4. In a weft detector for a loom having a regularly moving transerrer arm provided 80 with an indicating plunger slidably mounted on the transerrer arm and normally in non-indicating position, a detector carrier secured to and movable with the indicating plunger in a direction substantially parallel to the 85 length of the surface being detected, a detecting element slidably mounted on the carrier, yielding means to hold the detector normally in raised position relatively to the carrier, a depressor lever pivotally mounted on the transerrer arm and having operative contact with the detector element, said yielding means tending also to hold the depressor lever in normally raised position, 90 means to lower the depressor lever to cause the detecting element to move downwardly relatively to the carrier during the downward movement of the transerrer arm, and means thereafter tending to move the carrier and indicating plunger together with 95 the detecting element in a direction substantially parallel to the surface being detected, and movement being prevented when the detector engages a sufficient supply of 100 weft.

5. In a weft detecting mechanism for a loom having a regularly moving transerrer arm carrying an indicating plunger normally in non-indicating position, a detector carrier mounted to have sliding movement 110 relatively to the transerrer arm in a direction substantially parallel to the length of the surface being detected, a side slipping weft detector mounted on the carrier, yielding means to hold the detector normally in raised position, means effective during the downward movement of the transerrer arm to lower the detecting element against the action of the yielding means and relatively 115 to the carrier, and means thereafter tending to move the detector along the surface being detected, said carrier at substantial exhaustion of weft moving with the detector in a direction substantially parallel to the surface being detected and causing movement 120 of the indicating plunger from non-indicating to indicating position.

In testimony whereof I have hereunto affixed my signature.

KENNETH J. UNWIN.
